UNITED STATES PATENT OFFICE.

EARL H. VAN LOON, OF NEW YORK, N. Y., ASSIGNOR, BY MESNE ASSIGNMENTS, OF
ONE-HALF TO WILLIAM V. NELSON, OF NEW YORK, N. Y.

ELECTRIC PULL-SWITCH.

1,306,672.

Specification of Letters Patent. Patented June 10, 1919.

Application filed June 23, 1917. Serial No. 176,500.

To all whom it may concern:

Be it known that I, EARL H. VAN LOON, a citizen of the United States, residing at New York, in the county of New York and State 5 of New York, have invented new and useful Improvements in Electric Pull-Switches, of which the following is a specification.

This invention relates to a pull socket electric switch in which the actuating mechanism for making and breaking the circuit is provided with an arm projecting from the shell for attaching a flexible connection.

The invention is designed to comprehend means whereby the socket can be arranged in 15 any desired position without disconnecting the flexible connection.

The object of the invention is to provide readily accessible means for attaching the flexible connection so that when it accidentally breaks, it can be replaced on the 20 arm by any unskilled person.

Heretofore in electric sockets of the kind described above the flexible pull was secured to the mechanism at the inside of the shell, 25 hence when the connection was broken it became necessary to remove the cap from the shell and lift out the oscillating disk.

The invention resides in the novel combination of parts hereinafter fully described 30 and claimed, and illustrated in the accompanying drawing in which:

Figure 1 represents a side elevation of a socket embodying this invention.

Fig. 2 is a transverse section taken along 35 the line $\alpha\alpha$ of the same.

Fig. 3 is a similar section showing the parts in a different position.

In this drawing the letter a designates a shell provided with a cap b which when removed gives access to the interior of the shell. In the shell is secured a porcelain block c having mounted thereon an oscillating contact device including a disk d for opening or closing the electric circuit as is well known. In this device the center of oscillation of the make and break device is parallel with the longitudinal axis of the shell.

To the lower portion of the disk is secured 50 at e an arm f having a slot g at its outer portion. The arm projects from a circumferential slot h formed in the shell. A flexible connection or chain i has one end anchored or inserted in the slot of the arm. A spring 55 hook shaped mousing j covers the entrance of

the slot and prevents the chain from slipping out. The chain is threaded through an eyelet k secured to the outer portion of the shell. This eyelet is located slightly beyond the end of the slot as indicated in Fig. 2. 60 The eyelet being also in a direct line with the slot and arm, it will permit an even pull of the chain and easy operation of the arm.

It will be readily understood that the peculiar position of the chain guide in relation to the arm permits the socket to be placed in any position, for example, when used for an upright lamp, it can be inverted from the position indicated in Fig. 1 without disarranging the chain, or it can be placed 65 horizontally or at any angle for a drop lamp. When the chain is pulled the arm will slide along the segmental slot h in an arc of about 70 90° and the disk will swing in a concentric circle with the inner cylindrical portion of 75 the shell.

As shown in the drawing the hook of the mousing engages the mouth of the slot effectively preventing the end of the chain from being accidentally pulled from the arm, but 80 if the chain should be broken the end can be released from the slot by moving the spring hook outwardly.

I claim:

1. A pull socket electric switch comprising 85 a shell having a circumferential slot, an oscillating device projecting through the slot, a connection secured to the oscillating device on the outside of the shell and means on the outside of the shell adjacent to the slot end 90 for guiding the connection.

2. A pull socket electric switch comprising 95 a shell having a circumferential slot, an oscillating device extending through the slot, a connection secured to the device and means on the outside of the shell adjacent to the slot end for guiding the connection.

3. A pull socket electric switch comprising 100 a shell having a circumferential slot therein, an oscillating device extending through the slot, a connection secured to the oscillating device and means on the outside of the shell so placed as to guide the connection in such way that the switch can be operated in any position or angle it may be placed in by 105 pulling on the connection.

4. A pull socket electric switch comprising 110 a shell having a circumferential slot, oscillating devices for making and breaking the circuit mounted in the shell, a slotted arm

- secured to the devices and projecting from the slot, a flexible connection fitted in the slot of the arm, means for closing the mouth of the slot, and an eyelet secured to the shell
- 5 beyond the end of the slot for guiding the connection.
5. A pull socket electric switch comprising a shell, an oscillating device, a connection secured to the oscillating device, said shell
- 10 having a circumferential slot therein to permit of securing the connection to the oscillating device, and means on the outside of

the shell so placed as to guide the connection in such way that the switch can be operated in any position or angle it may be placed in 15 by pulling on the connection.

In testimony whereof I have hereunto set my hand in the presence of two subscribing witnesses.

EARL H. VAN LOON.

Witnesses:

GRACE DE VOE,
WILLIAM MILLER.
